OIL BURNER CONTROL SYSTEM

Albert E. Baak, Minneapolis, Minn., assignor to
 Minneapolis-Honeywell Regulator Company,
 Minneapolis, Minn., a corporation of Delaware

Application April 1, 1938, Serial No. 199,500

6 Claims. (Cl. 158—28)

The invention relates generally to automatic control systems for oil burners, and more specifically to an automatic oil burner control system having certain features of safety whereby dangers due to failure of ignition are minimized.

In certain types of control systems now in use it is the practice to provide a fuel pump or valve to control the delivery of fuel to the nozzle of the burner, and an igniter for igniting the fuel so delivered. The fuel delivery means and the ignition means are energized by a control instrument, such as a room thermostat, on a call for heat and after a predetermined time interval or after combustion has occurred an ignition switch is operated to break the circuit to the igniter while the fuel delivery means continues to function. After the room thermostat has become satisfied it will deenergize the fuel delivery means after which the ignition switch will reclose and the system will be in a condition to restart under the control of the room thermostat.

If, in a system of the above type, the ignition switch should stick in open position while the system is running or for some other reason should fail to reclose after the fuel delivery means is deenergized by the room thermostat, a subsequent call for heat by the room thermostat would energize the fuel delivery means, but due to the open ignition switch the ignition means would remain deenergized. This means that raw fuel would be forced into the combustion chamber which would not be ignited, and should the ignition switch later close, due to a slight jar for example, the resultant spark might cause an explosion due to 35 the large quantity of unburned fuel present.

It is a prime object of this invention to provide a safety feature which will make such a condition as described above impossible.

A further object is to provide an oil burner 40 control system where the circuit to the ignition means must be closed before the burner motor can be energized.

Another object is to provide an oil burner control system of the low voltage type wherein the 45 circuit for energizing the burner motor must first pass through a combustion switch by means of which the ignition means is energized.

These and other objects will become readily apparent to those skilled in the art as the following 50 specification is read in the light of the accompanying drawing, in which

Figure 1 is a circuit diagram of the control system of the present invention, with the parts 55 shown in the cold position, and

Figure 2 is the same circuit diagram with the parts shown in the running position.

The control system of this invention derives its power from the alternating current supply lines 11 and 12. One end of a primary winding 13 of 5 a step-down transformer 14 is connected by means of conductor 15 to the supply line 12. The other end of the primary 13 is connected by means of conductor 16 to a stationary contact 17 of a combustion switch generally indicated at 18. 10 This combustion switch cooperates with a second stationary contact 19 which is joined by means of conductor 20 to a conductor 21 which, in turn, connects with the supply line 11.

The combustion switch 18 is operated through 15 a slip friction connection by means of a thermostat (not shown) which is mounted in the stack leading from the furnace and comprises a flexible arm 22 and a rigid arm 23 connected together at one end. This switch is arranged so that on a 20 decrease in temperature, the flexible arm 22 will engage its contact 19 first, and a further decrease in temperature will cause it to flex and permit the rigid arm 23 to engage its contact 17. This flexing of the arm 22 will also produce a wiping action 25 on the contact 19 which will tend to keep it clean.

Step-down transformer 14 is provided with a secondary winding 24 which is connected at one 30 end by means of conductor 25 to a contact 26 of a safety switch generally indicated at 27. This safety switch is shown more or less diagrammatically as being comprised of a bimetallic element 28 and an electric heater 29. Actually, it is intended that this switch shall automatically 35 break its contact 26 after the heater 29 has been energized for a predetermined length of time, and that it shall be necessary to manually reset it to close the contact 26. The details of the switch mechanism do not form a part of this invention 40 and may take various forms, such for example as disclosed in the Denison Patent 1,958,081. The fixed end of the bimetallic element 28 is connected by means of conductor 30 to a stationary contact 31 of a combustion switch generally indicated at 32. A second stationary contact 33 of combustion switch 32 is connected by means of conductor 34 to one end of the heater 29, the other end of which is connected by conductor 35 to the conductor 30.

The combustion switch 32 is shown diagrammatically as being provided with a contact arm 36 which makes contact with the two stationary contacts 31 and 33. The contact arm 36 is to be 50 operated through a slip friction connection by 55

means of a thermostat located in the stack, and on an increase in temperature the arm 36 will close the hot contact 31 before the cold contact 33 is broken, and on a decrease in temperature the 5 hot contact 31 will be broken before the cold contact 33 is made. This switch is shown diagrammatically and actually may take any one of a number of forms, one of which is disclosed in the Denison Patent 1,941,540. It might be pointed out also that both of the combustion switches 10 and 32 may be operated by the same stack thermostat. The contact arm 36 is connected by means of conductor 37 to one end of a relay coil 38, the other end of which is connected by means 15 of conductor 39 to a stationary contact 40. The other end of the secondary winding 24 is connected by means of conductor 41 to stationary contact 42.

A room thermostat generally indicated at 43 20 comprises a bimetallic coil 44 to which are connected a flexible arm 45 and a rigid arm 46. On a decrease in temperature the flexible arm 45 makes contact first with the stationary contact 42, and a further decrease in temperature causes 25 the arm 45 to flex and permit the rigid arm 46 to make contact with its stationary contact 40.

Relay coil 38 operates an armature which is diagrammatically shown as a dotted line 47 in the drawing. Energization of the relay 38 will 30 cause the armature 47 to move to the left and carry with it four switch arms 48, 49, 50, and 51. A conductor 52 connects the relay coil 38 to the switch arm 48 which cooperates with a stationary contact 53 connected by means of conductor 54 35 to the bimetallic element 44 of the room thermostat. The switch arm 49 is connected by means of conductor 55 to the conductor 16 and cooperates with stationary contact 56 which is connected by means of conductor 57 to the junction of the conductors 20 and 21. Switch arm 50 cooperates with a stationary contact 58 which is connected by means of conductor 59 to the ignition means 60. The purpose of switch 58-59 is to prevent a feed back from line 12, conductor 15, primary winding 13, conductor 16, switch 17-23, conductor 61, ignition means 60, conductor 59 to conductors 62 and 64, motor 63, and conductor 65 back to line 11. This condition would occur when switch 17-23 was closed and the 50 thermostat 44 was satisfied. Ignition means 60 is also connected by conductor 61 to the switch blades 22 and 23 of the combustion switch 18. Switch arms 50 and 51 are connected together by means of conductor 62 and to burner motor 63 by means of conductor 64. Conductor 65 connects the burner motor to the supply line 11. Contact arm 51 cooperates with a stationary contact 66 which is connected by means of conductor 67 to the other supply line 12.

60

Operation

Figure 1 discloses the elements of the system in their cold position, that is the room thermostat is satisfied and the thermostat responsive to 65 stack temperatures is cold and the system is, therefore, shut down. Assume now that the room begins to cool causing the bimetallic element 44 to move its switch arms 45 and 46 to the left. As a result of such cooling, switch arm 45 will 70 first make contact with stationary contact 42, at which time no circuit will be closed due to the fact that the switch 40-46 will be open and the switch 48-53 will be open. The room will, therefore, continue to cool until the thermostat has 75 caused engagement of the rigid arm 46 with its

stationary contact 40. The relay coil 38 will now be energized if the primary 13 of the transformer 14 has been connected to the supply conductors 11 and 12. This will depend upon the position of the blades 22 and 23 of the combustion switch 18. If these two switch arms have engaged the stationary contacts 17 and 19, a circuit will be completed from supply line 12 through conductor 15, primary winding 13, conductor 16, stationary contact 17, rigid arm 23, flexible arm 22, stationary contact 19, and conductors 20 and 21 back to the other supply line 11. If such a circuit exists the primary of the transformer 14 will be energized and the relay coil 38 will therefore be energized through the following circuit: secondary 15 winding 24 of transformer 14, conductor 41, stationary contact 42, flexible arm 45, rigid arm 46, contact 40, conductor 39, relay coil 38, conductor 37, contact arm 36 of the combustion switch 32, cold contact 33, conductor 34, heater 29 20 of the safety switch 27, conductor 35, conductor 30, bimetallic element 28, contact 26, and conductor 25 back to the other side of the secondary winding 24.

Energization of the relay 38 will pull in the 25 four arms 48, 49, 50, and 51. Engagement of the arm 48 with its contact 53 will set up the following holding circuit for the relay coil 38: secondary winding 24, conductor 41, contact 42, switch arm 45, bimetallic coil 44, conductor 54, contact 53, 30 switch arm 48, conductor 52, relay coil 38, conductor 37, switch arm 36, contact 33, conductor 34, heater 29, conductors 35 and 30, bimetallic element 28, contact 26, and conductor 25 back to secondary winding 24. It will be noted that this holding circuit does not pass through the switch contact 40 or rigid arm 46 of the thermostat 43 which means that the relay will be held in until the spring arm 45 breaks the circuit at its contact 42.

When switch arm 49 makes contact with the contact 56, it closes a circuit for the primary winding 13 which is independent of the contacts 17 and 19 of the combustion switch 18. This circuit is traced as follows: supply conductor 12, conductor 15, primary winding 13, conductors 16 and 55, switch arm 49, contact 56, and conductors 57 and 21 to supply conductor 11.

Engagement of contact 58 by switch arm 50 and contact 66 by switch arm 51 causes energization 50 of both the ignition means and the burner motor. The ignition means is energized through the following circuit: supply conductor 11, conductors 21 and 20, contact 19, flexible arm 22 of combustion switch 18, conductor 61, ignition means 60, 55 conductor 59, contact 58, switch arm 50, conductor 62, switch arm 51, contact 66, and conductor 67 back to supply conductor 12. The burner motor is energized by the circuit from conductor 12, conductor 67, contact 66, switch arm 51, 60 conductor 64, burner motor 63, and conductor 65 back to the supply conductor 11.

The conditions which obtain then when the room thermostat first makes its call for heat are that the relay 38 will be pulled in thus energizing 65 the ignition means and the burner motor, the safety switch will be closed, and the combustion switch 18 will be closing its two contacts and the combustion switch 32 will have its cold contact 33 closed. Normally, under the above 70 conditions, ignition will take place and the heat of the burner will pass up the stack to heat the thermostat which operates the two combustion switches. This will cause the contact arm 36 to engage the hot contact 31 and shunt out the 75

heater 29 of the safety switch 27. This circuit will be as follows: secondary winding 24, conductor 41, contact 42, switch arm 45, bimetallic element 44, conductor 54, contact 53, switch arm 48, conductor 52, relay coil 38, conductor 37, contact arm 36, hot contact 31, conductor 30, bimetallic element 28, contact 26, and conductor 25 back to the other side of the secondary winding 24. A further increase in stack temperature will cause the contact arm 36 to break the cold contact 33 which definitely breaks the circuit connection to the heater 29.

The increase in stack temperature will also cause the combustion switch 18 to leave its stationary contacts 17 and 19. No change will occur when the rigid arm 23 separates from the contact 17 due to the fact that this switch has already been shunted by the closure of the switch arm 49 with its stationary contact 56. However, disengagement of the spring arm 22 with the stationary contact 19 will cause deenergization of the ignition means 60, and the burner motor will remain energized through the switch arm 51 and contact 66. The system will now be in its hot or running position with the parts in the position shown in Figure 2.

The operation of the burner motor will cause heat to be supplied to the room which will warm up the room thermostat and cause it to first separate rigid arm 46 and stationary contact 40. This will produce no circuit change due to the fact that a holding circuit for the relay coil 38 has been set up through the switch arm 48 and contact 53. Further increase in room temperature will cause the flexible arm 45 to separate from stationary contact 42, which will deenergize the relay coil 38 and drop out the four switch arms 48, 49, 50, and 51. As switch arm 51 leaves its contact 66, the burner motor will become deenergized and the temperature in the stack will decrease which will cause the two combustion switches 18 and 32 to swing to the left and assume the positions shown in Figure 1.

The above description of the operation of the system is the normal operation, but as pointed out in the objects, this invention is directed to certain features of safety to take care of abnormal conditions. The operation of these safety features will now be described.

Assume, for example, that as the room thermostat became satisfied dropping out the relay 38 and the stack temperatures commenced to drop that the combustion switch 18 became stuck and the flexible arm 22 did not make contact with its stationary contact 19. It will be noted that this is the switch through which the ignition means is energized and which breaks as combustion is obtained to cut off the ignition means. If now the burner motor were energized on a call for heat, there would be no spark to ignite the fuel and the raw fuel would be pumped into the furnace. With the present system, it can readily be seen that it is impossible now to energize the burner motor because after the relay coil 38 has been dropped out the primary winding 13 of the transformer 14 depends for energization on a circuit which includes resilient arm 22 and its stationary contact 19. Therefore, if this switch or switch 23-17 is not closed, there will be no power in the transformer and the relay coil 38 cannot be pulled in to energize the burner motor. This feature which prevents the burner motor from being energized when no ignition is available is one of the main purposes of this invention.

Assume now that the combustion switch 18 had

closed its circuits and that the room thermostat had pulled in the relay 38 to start the system in operation. It might occur that from some reason, although the circuit to the ignition means was closed, that the fuel failed to ignite. If such a condition occurred, there would be no combustion and hence the stack temperature would not increase so that the combustion switches 18 and 32 remain in the positions shown in Figure 1. In this case, the heater 29 for the safety switch 27 would not be shunted out of circuit and would eventually heat the thermostat 28 to the point where it would break the circuit at contact 26. This would drop out the relay 38 and the burner motor and ignition means would be shut down. It would then be necessary to locate the cause of the trouble and manually reset the safety switch. This feature of safety is customary in the art at present and is not a part of this invention.

Assume now that the room thermostat has called for heat and started the burner motor, that ignition has taken place, and that the system is running with the parts shown as in Figure 2. It might occur that due to dirt in the oil line or some other reason, the flame in the furnace should become extinguished while the room thermostat was still calling for heat and the burner motor was still operating. It will be remembered that at this time the combustion switch 18 will have caused separation of the flexible arm 22 and its contact 19 due to an increase in the stack temperature. Therefore, when the flame fails there can be no immediate spark to reignite it. In such a case as this, the stack temperature will immediately begin to fall and the contact arm 36 will leave its hot contact 31 which will break the circuit to the relay 38 dropping out the switch arms 48, 49, 50, and 51 and therefore, deenergize the burner motor. The system will remain shut down in this fashion until the contact arm 36 has closed its cold contact 33 and until the combustion switch 18 has caused the rigid arm 23 to engage its contact 17 and the flexible arm 22 to engage its contact 19. The room thermostat will still be calling for heat and it will now pull in the relay 38 and attempt to restart the system in the normal manner. If the trouble which caused extinguishment of the flame has been corrected, the system will start up and operate normally, but if the trouble is still present the burner will not ignite. Pulling in the relay 38 will not cause an increase in stack temperature so that the heater 29 of the safety switch 27 will remain energized, and after a predetermined length of time cause the safety switch to open the circuit with contact 26. It will now be necessary to locate the trouble and correct it and manually reset the safety switch.

Another thing which might happen when the system is in the running position as shown in Figure 2 is that the electric power might fail. In this case, the relay 38 will immediately become deenergized and drop its switch arms and the stack will begin to cool. If the power should come on immediately while the combustion switches are still in the position shown in Figure 2, the burner motor cannot be energized because of the fact that the switch arm 51 will not be in contact with its stationary contact 66. The system will remain shut down until the combustion switches have returned to the position shown in Figure 1 and it will be necessary to pull in the relay 38 through the heating element 29 of the safety switch 27 and to close the circuit to the

ignition means as in starting up under a normal operation. This is a very desirable feature because it will be remembered that when the combustion switches are in their hot position the circuit to the ignition means is broken, and therefore if it were possible to energize the fuel burner it would only act to pump the raw fuel into the furnace.

It will thus be seen that with the system of this invention, it is impossible at any time to cause energization of the burner motor without at the same time causing energization of the ignition means. This is the main feature of this invention and it is a very desirable result in producing automatic control systems for oil burners in that it minimizes the chances for an explosion due to the ignition of a relatively large quantity of raw fuel.

Modifications of this invention may occur to those skilled in the art for performing the same function, and it is therefore to be understood that I am to be limited not by the specific embodiment herein disclosed but rather by the scope of the appended claims.

25 I claim as my invention:

1. An electrical control system for liquid fuel burners comprising a high voltage supply, a step-down transformer having a primary winding and a secondary winding, a combustion responsive switch which is closed on lack of combustion and opened when combustion occurs, means for connecting said primary winding to said high voltage supply including said combustion responsive switch, an ignition means, means for connecting said ignition means to said high voltage supply including said combustion responsive switch, a burner motor, means for connecting said burner motor to said high voltage supply including a normally open switch, a relay, means for connecting said relay to said secondary winding including a condition responsive switch, means for maintaining said relay energized independently of said combustion responsive switch, and means associated with said relay for closing said normally open switch.

2. An electrical control system for liquid fuel burners comprising a high voltage supply, a step-down transformer having a primary winding and a secondary winding, a combustion responsive device, two switches operated thereby to closed position on lack of combustion and open position when combustion occurs, means connecting the primary winding to said high voltage supply including both of said switches, a first normally open switch for shunting both of said switches out of control, an ignition means, means for connecting said ignition means to said high voltage supply including one of said combustion switches and a second normally open switch, a burner motor, means for connecting said burner motor to said high voltage supply including a third normally open switch, a relay, means for connecting said relay to said secondary winding including a condition responsive switch, and means associated with said relay for closing said normally open switches.

3. A control system for fluid fuel burners comprising in combination, an electrical fuel feeding device, an ignition device for the fuel, a circuit for said electrical fuel feeding device, a relay which when energized closes said circuit to said fuel feeding device, first switch means responsive to the demand for heat in circuit with said relay, a circuit for said ignition device also closed upon energization of said relay, and in-

cluding a further switch means so arranged that the flow of current through said ignition device is independent of said first switch means except as said first switch means controls the operation of said relay, means for moving said second switch means to open position following the successful establishment of combustion, and means preventing the original energization of said relay by said first switch means unless said second switch means is in condition to pass current. 10

4. A control system for fluid fuel burners comprising in combination, a source of power, a transformer having primary and secondary windings, switch means, means connecting said primary winding across said source of power 15 including said switch means, an electrical fuel feeding device, an ignition device for the fuel, a relay, a condition responsive device in circuit with said secondary winding for operatively energizing said relay, said relay upon energization 20 establishing a circuit for said primary winding independent of said switch means, a circuit for said fuel feeding device and a circuit for said ignition device, the circuit for said ignition device including said switch means, and means for moving said switch means to open position following successful combustion.

5. A control system for fluid fuel burners comprising in combination, a source of power, a transformer having primary and secondary 30 windings, switch means, means connecting said primary winding across said source of power including said switch means, an electrical fuel feeding device, an ignition device for the fuel, a relay, a condition responsive device in circuit 35 with said secondary winding for operatively energizing said relay, said relay upon energization establishing a circuit for said primary winding independent of said switch means, a circuit for said fuel feeding device and a circuit for said 40 ignition device the circuit for said ignition device including said switch means, means for automatically moving said switch means to open position to terminate ignition after said fuel feeding device has been energized and for automatically reclosing said switch means as an 45 incident to the termination of combustion.

6. A control system for fluid fuel burners comprising in combination, a source of power, a transformer having primary and secondary 50 windings, switch means, means connecting said primary winding across said source of power including said switch means, an electrical fuel feeding device, an ignition device for the fuel, a relay, a condition responsive switch in circuit 55 with said secondary winding for operatively energizing said relay, said relay upon energization establishing a circuit for said primary winding independent of said first named switch means, a circuit for said fuel feeding device and a circuit 60 for said ignition device, both circuits being normally closed upon energization of said relay, the circuit for said ignition device including said first named switch means so arranged that the flow of current through said ignition device is 65 independent of said condition responsive switch except as said condition responsive switch controls the operation of said relay, means for automatically moving said first named switch means to open position to terminate ignition after said 70 fuel feeding device has been energized and for automatically reclosing said switch means as an incident to the termination of combustion.
